UNITED STATES PATENT OFFICE.

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

CAR COUPLER.

Application filed November 29, 1924. Serial No. 752,889.

To all whom it may concern:

Be it known that I, WILLIAM KELSO, a citizen of the United States, residing at Pittsburgh, in the county of Allegheny and State of Pennsylvania, have invented certain new and useful Improvements in Car Couplers; and I do hereby declare the following to be a full, clear, and exact description of the invention, such as will enable others skilled in the art to which it appertains to make and use the same.

This invention relates to car couplers and more particularly to the mechanism whereby the rotatable knuckle is normally locked in coupled position.

The primary object of the invention is to provide simple, efficient and readily assembled means for moving the coupler lock to unlocked position and for preventing it from accidentally assuming an unlocked position when the device is in service.

The principal feature of the invention consists in providing the lock for the knuckle with a depending leg which extends through an opening in the coupler head and is formed with a plurality of intersecting slots, means movable with respect to the lock being associated therewith for the purpose of preventing an accidental unlocking movement of said lock, and an uncoupling member being used for actuating said means and for actuating said lock through the intermediacy of said means, one of the intersecting slots of the lock leg being adapted to receive the said means and one of said slots being adapted to receive the uncoupling member, and the portion of the said means which extends into the slot being apertured to receive the uncoupling member and being adapted to move vertically with respect to the lock as well as to oscillate angularly.

A further feature of the invention consists in providing the lock for the knuckle with a depending leg having an elongated slot and in movably mounting thereon means for preventing an accidental unlocking movement thereof, said means being formed with an arm adapted to extend under and cooperate with a portion of the coupler head so as to maintain the lock in locked position and being provided with a

lug which is slidably and angularly movable within the slot of the lock leg and also being formed with a projection between which and said arm the depending lock leg extends.

Another feature of the invention consists in providing the lock for the knuckle with a depending leg having a plurality of intersecting slots and formed with a shoulder affording a bearing upon which a lock controlling member is adapted to rock, and in combining therewith a lock controlling member adapted to cooperate with the coupler head to prevent accidental unlocking of said lock, together with an uncoupling member adapted to actuate the lock controlling member and also to actuate the lock through the intermediacy of the said controlling member, the latter being provided with a lug that is slidably and angularly movable within one of the slots of the lock leg, and also being formed with a projection for engaging and rocking upon the said shoulder to cause a corresponding swinging movement of the lock controlling member, and the uncoupling member being received by the other slot and engaging said lug so as to maintain the lock controlling member in assembled relation to the lock.

A still further feature of the invention consists in providing the lock for the knuckle with a depending leg formed with an elongated slot and with a shoulder constituting a bearing upon which the lock controlling member is adapted to rock, and in combining therewith a lock controlling member movable with respect thereto, and an uncoupling member adapted to actuate the latter and the said lock, the lock controlling member having an arm for cooperating with the coupler head to prevent accidental unlocking of the lock and having a lug slidably and angularly movable within the slot of the lock leg and being provided with a projection for engaging and rocking upon said shoulder of the lock leg and also being formed with a lug spaced laterally from said projection and constituting an actuating weight for causing the lock controlling member to execute, under the influence of gravity, a rocking movement with respect to said lock leg.

Other features of the invention residing

in advantageous forms and relations of parts will hereinafter appear and be particularly pointed out in the claims.

In the drawings illustrating the invention,—

Figure 1 is a transverse section of a car coupler embodying the invention, the parts being in locked position.

Figure 2 is a detail view corresponding to Fig. 1 but illustrating the coupler lock as having been released from the control of the device by which it is retained in locked position.

Figure 3 is a view in side elevation of the lower portion of the lock and associated lock controlling device.

Figure 4 is a detail rear elevational view of the lower portion of the coupler lock and associated lock controlling device.

Figure 5 is a detail view partly in plan and partly in section on the line 5—5, Fig. 2.

Figure 6 is a transverse sectional view of a car coupler embodying a modified form of the invention.

Figure 7 is a detail sectional view corresponding to Fig. 6 but illustrating the lock controlling member in a position permitting the lock to perform an unlocking movement.

Figures 8 and 9 are detail views in side and rear elevation, respectively, of the lower portion of the coupler lock and the lock controlling mechanism.

Figure 10 is a detail sectional view on the line 10—10, Fig. 8.

The coupler illustrated for the purpose of explaining the invention is a well known form of the Master Car Builders' type. It is to be understood, however, that the invention is not restricted to a coupler of that form although it is especially well adapted for such a mechanism.

In the drawings, 1 indicates the coupler head, 2 is the knuckle pivotally mounted thereon, and 3 is a rotatable knuckle opener adapted to be actuated by the coupler lock 4 when the latter performs an extended unlocking movement. The lock is provided with a depending leg 5 which extends downwardly through an opening 6 in the under side of the coupler head. At its lower end the lock leg is formed with a plurality of elongated intersecting slots 7 and 8, respectively; the former being adapted to receive a portion of the lock controlling member, and the latter being for the reception of an uncoupling rod or lever for actuating the knuckle locking mechanism. At one side of the slot 8 the lock leg is fashioned with a downwardly facing shoulder 9 forming a bearing face upon which the means 10 by which the lock is prevented from accidentally assuming an unlocked position are adapted to rock; and above said slot the depending lock leg 5 is preferably provided with a shoulder 11 adapted to engage the

lock controlling member 10 for the purpose of limiting the swinging movement of the latter toward the lock 4.

The lock controlling member 10 which is movably mounted upon the lock 4 is formed with an arm 12 whose upper end is preferably stepped so as to provide a shoulder 13 adapted to stand beneath a portion 14 of the coupler head and thus prevent the lock 4 from accidentally executing an unlocking movement. The portion 15 of the arm 12 which is above the shoulder 13 and projects into the opening 6 of the coupler head is adapted, as shown in Fig. 1, to engage said head so as to limit the extent of swinging movement of the lock-to-the-lock device 10 away from the lock 4.

Near its lower end the lock controlling member 10 is provided on one side with a lug 16 adapted to be received by the slot 7 in the lock leg 5. The lug 16, which preferably lies in a plane disposed at a slight angle to the direction of length of the upwardly extending arm 12, is adapted to slide vertically and also to oscillate angularly within said slot. The lug 16 is preferably of greater height than width and has an aperture 17 in alignment with the slot 8 for the purpose of receiving an uncoupling member or bar 18. As well shown in Figs. 1, 2 and 3, the opening 17 in the lock-to-the-lock member 10 is preferably flared or enlarged at one side so as to permit the said part 10 to shift its angular position with respect to the uncoupling member 18 when the latter is operated to unlock the coupler. At its outer end the lug 16 is preferably provided with an upwardly extending inclined projection 19 which overlaps the lock leg 5 above the slot 7 for receiving the lug portion 16 of the lock-to-the-lock member. The projection 19 and upwardly extending arm 12 by overlapping opposite sides of the lock leg 5 assist in maintaining the lock controlling member 10 in proper operative relation to the lock 4, particularly during the unlocking movement of the latter.

To cause the arm 12 of the lock controlling member to swing from beneath the shoulder 14 on the coupler head and assume a position permitting the lock 4 to be raised when the uncoupling member 18 is operated, the controlling member 10 is fashioned with a projection or upwardly facing shoulder 20 which is adapted to cooperate with the downwardly facing bearing shoulder 9 of the lock leg. As the projection 20 and shoulder 9 engage each other at one side of the point of contact of the uncoupling member 18 with the lug 16 of the lock-to-the-lock member 10, an upward or uncoupling movement of the uncoupling member results in causing the upper end of the lock controlling member 10 to swing toward the depending leg of the lock 4,

thereby freeing the lock so that it may be moved to unlocked position.

The lock-to-the-lock member 10 is designed to be actuated by gravity so as automatically to move to a position beneath the shoulder 14 on the coupler head when the lock 4 falls to a locked position. In the embodiment of the invention illustrated in Figs. 1 to 5, inclusive, the lock controlling member 10 is for this purpose preferably provided on the side opposite the projection 20 with a lug or projection 21 which constitutes an actuating weight for causing the lock controlling member to rock with respect to the lock leg 5 so as to assume a position preventing accidental unlocking of the lock 4.

The uncoupling member 18 which extends through a slot 8 of the lock leg and through the apertured lug 16 of the lock controlling member 10 serves, it will be perceived, to maintain said lock controlling member in assembled relation to the lock.

When the uncoupling member 18 is actuated for the purpose of unlocking the coupler its initial upward movement causes the lock controlling member to swing toward the lock and assume the position shown in Fig. 2. After the lock has thus been released from the control of the lock-to-the-lock member 10 the continued upward movement of the uncoupling member 18 raises the lock 4, causing it to assume unlocked position.

In the modified form of the invention illustrated in Figs. 6 to 10, inclusive, the coupler head 1, pivoted knuckle 2 and knuckle opener 3 are the same in construction as the corresponding parts heretofore described. The form of knuckle lock 22 is, however, somewhat different in respect of its depending leg 23. It is, as in the case of the lock leg 5, provided near its lower end with intersecting slots 7 and 8, respectively, corresponding in form and function to the similar slots heretofore described, and it has a vertically extending shoulder 11 adapted to be engaged by the lock controlling member for the purpose of limiting the tilting movement of the latter toward the lock 22; but it is unprovided with a downwardly facing shoulder 9 which, in the case of the construction shown in Figs. 1 to 5, forms a bearing or seat upon which the projection 20 of the lock controlling member 10 rocks, and it also omits the lug 21 constituting an actuating weight for the purpose of causing the shoulder 24 at the upper end of the lock controlling member 25 to move outwardly from the lock and assume a position beneath the shoulder 14 of the coupler head when the lock 22 is in locked position. The lock leg 23 is formed near its upper end with an inclined face or shoulder 26 adapted to cooperate with a correspondingly in-

clined face 27 at the top of the upwardly extending arm 28 of the lock-to-the-lock member 25. The lock 22 also preferably differs from the lock 4 in being provided on one side below the slot 7 with a lug or projection affording a vertically extending face 29 which the downwardly extending projection 30 of the lock controlling member 25 engagingly overlaps to assist in guiding said lock controlling member when the latter moves with respect to the lock 22.

The lock controlling member 25, whose upper end 13 extends into the opening 6 of the coupler head, is formed near the lower end of its locking arm 28 with a lug 32 adapted to be received by the slot 7 of the lock leg 23. The lug 32 preferably lies in a plane disposed at a slight angle to the direction of length of the upwardly extending arm 25 and is adapted to slide vertically and also to oscillate angularly within said slot. An aperture 33 is formed in the lug 32 in alignment with the slot 8 for the purpose of receiving the uncoupling bar or rod 18; and at its outer end the lug 32 is preferably formed with a downwardly extending projection or portion 30 which overlaps the guiding face 29 of the lock leg below the slot 7 in which the said lug is received.

It will be perceived that the uncoupling member by extending through the slot 8 of the lock leg and through the apertured lug 32 of the lock controlling member 25 serves to maintain said lock controlling member in assembled relation to the lock 22.

When the uncoupling member 18 is moved upwardly for the purpose of effecting an unlocking of the coupler its initial upward movement raises the lock controlling member 25, causing the inclined shoulder 24 at the upper end of the latter to slide upon the shoulder 14 of the coupler head and thereby effect a tilting of the lock-to-the-lock member with respect to the lock. This tilting of the lock controlling member 25 causes its locking shoulder 24 to be withdrawn from beneath the portion 14 of the coupler head, as shown in Fig. 7, thus freeing the lock 22 so that the latter may move upwardly to unlocked position. After the lock has thus been released from the control of the lock-to-the-lock member 25 the continued upward movement of the uncoupling member 18 effects the unlocking of the lock 22.

I claim:

1. A car coupler having a head, a knuckle pivotally mounted thereon, a lock for said knuckle having a depending leg extending through an opening in said head, means movable with respect to the lock for locking the latter against accidental unlocking movement, and an uncoupling member adapted to actuate said means and to actuate said lock through the intermediacy of said means, said leg being formed with a plurality of

intersecting slots one of which is adapted to receive said means and one of which is adapted to receive said uncoupling member, and the portion of said means which extends into said slot in the lock being apertured to receive said uncoupling member and being adapted to move vertically with respect to said lock and also to oscillate angularly.

2. A car coupler having a head, a knuckle pivotally mounted thereon, a lock for said knuckle having a depending leg extending through an opening in said head, means movable with respect to said lock for preventing accidental unlocking of the latter, and an uncoupling member adapted to actuate said means and to actuate said lock through the intermediacy of said means, said leg being provided with an elongated slot, and said means being provided with a lug of greater height than width which extends into said slot and is adapted to move vertically with respect to said lock and also to oscillate angularly.

3. A car coupler having a head, a knuckle pivotally mounted thereon, a lock for said knuckle having a depending leg extending through an opening in said head, means movable with respect to said lock for preventing accidental unlocking of the latter, said means being provided with a lug, and an uncoupling member adapted to actuate said means and to actuate said lock through the intermediacy of said means, said leg being provided with a plurality of intersecting elongated slots one of which is adapted to receive said lug and one of which is adapted to receive said uncoupling member, said lug being movable in said slot, and said uncoupling member being adapted to retain said lug in operative position within said slot.

4. A car coupler having a head, a knuckle, a lock for said knuckle having a depending leg extending through an opening in said head, means movable with respect to said lock for locking the latter against accidental unlocking, said means involving an arm adapted to stand under and cooperate with a portion of said head, and an uncoupling member adapted to actuate said means and to actuate said lock through the intermediacy of said means, said leg being provided with an elongated slot, and said means being provided with a lug which is slidably and angularly movable within said slot and is formed with a projection between which and said arm said depending leg extends.

5. A car coupler having a head, a knuckle, a lock for said knuckle having a depending leg extending through an opening in said head, means movable with respect to said lock for locking the latter against accidental unlocking, and an uncoupling member adapted to actuate said means and to actuate said lock through the intermediacy of said means, said uncoupling member when

in operative position serving to maintain said means in assembled relation to said lock, said leg being provided with an elongated slot, said means being provided with a lug which is slidably and angularly movable within said slot, and said means and said depending leg being provided with cooperating parts serving to move said means so as to effect an angular movement of said lug within said slot.

6. A car coupler having a head, a knuckle, a lock for said knuckle having a depending leg extending through an opening in said head, a lock controlling member adapted to cooperate with said head to prevent accidental unlocking of said lock, and an uncoupling member adapted to actuate said lock controlling member and said lock, said leg being provided with an elongated slot and having a shoulder forming a bearing upon which said lock controlling member is adapted to rock, and said lock controlling member being provided with a lug which is slidably and angularly movable within said slot and also being provided with a portion for bearing against and rocking upon said shoulder to cause said lock controlling member to assume a position permitting said lock to execute an unlocking movement.

7. A car coupler having a head, a knuckle, a lock for said knuckle having a depending leg extending through an opening in said head, a lock controlling member adapted to cooperate with said head to prevent accidental unlocking of said lock, and an uncoupling member adapted to actuate said lock controlling member and to actuate said lock through the intermediacy of said lock controlling member, said leg being formed with a plurality of intersecting slots, said lock controlling member being provided with a lug which is slidably and angularly movable within one of said slots, said uncoupling member being received by the other of said slots and engaging said lug to maintain said lock controlling member in assembled relation to said lock, said leg having a shoulder forming a bearing upon which said lock controlling member is adapted to rock, and said lock controlling member being provided with a projection for engaging and rocking upon said shoulder to cause a corresponding swinging movement of said lock controlling member.

8. A car coupler having a head, a knuckle, a lock for said knuckle having a depending leg extending through an opening in said head, a lock controlling member having an arm adapted to cooperate with said head to prevent accidental unlocking of said lock, and uncoupling means adapted to actuate said lock controlling member and to actuate said lock through the intermediacy of said lock controlling member, said leg being provided with an elongated slot and having a

shoulder forming a bearing upon which said lock controlling member is adapted to rock, and said lock controlling member having a lug which is slidably and angularly movable within said slot and having a projection for engaging and rocking upon said shoulder and also having an upwardly extending projection overlapping said depending leg above said slot on the side opposite said arm.

9. A car coupler having a head, a knuckle, a lock for said knuckle having a depending leg extending through an opening in said head, a lock controlling member movable with respect to said lock and having an arm adapted to cooperate with said head to prevent accidental unlocking of said lock, and an uncoupling member adapted to actuate said lock controlling member and to actuate said lock through the intermediacy of said lock controlling member, said leg being provided with an elongated slot and having a shoulder forming a bearing upon which said lock controlling member is adapted to rock, said lock controlling member having a lug which is slidably and angularly movable within said slot and having a projection for engaging and rocking upon said shoulder and also having a lug spaced laterally from

said projection for constituting an actuating weight to cause said lock controlling member to rock with respect to said lock leg so as to assume a position preventing accidental unlocking of said lock.

10. A car coupler having a head, a knuckle, a lock for said knuckle having a depending leg extending through an opening in said head, a lock controlling member having an arm adapted to cooperate with said head to prevent accidental unlocking of said lock, and an uncoupling member adapted to actuate said lock controlling member and to actuate said lock through the intermediacy of said lock controlling member, said leg being formed with a plurality of elongated slots and having a shoulder forming a bearing upon which said lock controlling member is adapted to rock, said lock controlling member having an apertured lug which is slidably and angularly movable within one of said slots and having a projection for engaging and rocking upon said shoulder, and said uncoupling member being received by the other of said slots and the aperture of said lug.

In testimony whereof I affix my signature.

WILLIAM KELSO.
